UNITED STATES PATENT OFFICE.

EDGAR S. ENGLE, OF GREENSBURG, PENNSYLVANIA.

BOTTLE-FILLING MACHINE.

Application filed February 18, 1927. Serial No. 169,332.

This invention relates to a bottle filling and capping machine, the general object of the invention being to provide means for forcing a bottle against a discharge spout of a tank, 5 which action opens the spout and permits some of the contents of the tank to enter the bottle, after which the bottle is lowered which permits the spout to close.

This invention also consists in certain other 10 features of construction and in the combination and arrangement of the several parts, to be hereinafter fully described, illustrated in the accompanying drawings and specifically pointed out in the appended claims.

15 In describing my invention in detail, reference will be had to the accompanying drawings wherein like characters denote like or corresponding parts throughout the several views, and in which:

20 Figure 1 is a vertical sectional view of portion of a machine constructed in accordance with this invention.

Figure 2 is an elevation with parts in section of the lifting and rotating means.

25 Figure 3 is a view similar to Figure 2, but showing the parts in a different position.

Figure 4 is a section on line 4—4 of Figure 1.

30 Figure 5 is a section on line 5—5 of Figure 1.

Figure 6 is a sectional view through the filling means, showing the same moved to open position by a bottle.

35 Figure 7 is a section on line 7—7 of Figure 1.

Figure 8 is a view showing how the parts can be operated with a motor.

In these views, 1 indicates a part of a supporting frame which includes posts, one of 40 which is shown at 2, which support the base 3 for the tank 4. The post 2 has a slot 6 which forms a guideway for a pin 7 carried by a head 8 which is slidably mounted in the hollow post 2 and connected to a rod 9 which

45 is adapted to be reciprocated by the movement of a pedal lever 10 which is pivoted to a part of the frame. A toothed sleeve 11 is slidably mounted on the front post 2 and a long sleeve 12 is also slidably mounted on said post above the sleeve 11, this sleeve 12 also being provided with teeth 13 at its bottom for engaging the teeth 14 of the sleeve 11. These teeth are of cam shape so that as the sleeve 12 is raised, the inclined edges of its teeth, leaving the in-

50 clined edges of the teeth of sleeve 11, will rotate said sleeve 11 and cause it to ride up a

beveled projection 15 on a base part of the post 2 which normally engages a notch 16 in the bottom of the sleeve 11, said notch having a beveled wall. Then when the upper sleeve 60 frees the lower sleeve, said sleeve will return to its original position under the action of gravity and then when its teeth are engaged by the teeth of the upper sleeve as said upper sleeve drops under the action of gravity, the 65 said upper sleeve will be given a quarter revolution. Both sleeves are slotted, as at 17, to receive the ends of the pin 7, but the slot in the upper sleeve is short so that after the pin has been moved a certain extent by the pedal 70 means, it will engage the upper end of the slot in the upper sleeve and thus raise said sleeve. A tubular guide 18 is connected with the lower sleeve and surrounds the lower part 75 of the upper sleeve.

A pair of bottle carrying disks 19 and 20 are adjustably connected with the upper portion of the upper sleeve by the set screws 21 and the disk 19 is formed with a number of flanged recesses 22 in its periphery for receiving the necks of bottles, such as shown at A, and the disk 20 is provided with a number of shallow recesses 23 which are arranged to receive parts of the necks of the bottles held in the recesses 22 of the disk 19 so that these 80 two disks hold the bottles against movement.

85 From the foregoing, it will be seen that by depressing the foot pedal, the pin 7 will engage the upper sleeve, thus raising the same so that the bottle carrying disks are raised 90 and then as the pedal is depressed, the parts will descend and the engagement of the teeth of one sleeve with the teeth of the other sleeve will give the upper sleeve and the disks carried thereby a quarter revolution so as to bring a new bottle under the filling means and to position the bottle just filled under the capping means.

95 Instead of having the parts operated by manual power, they can be operated by a motor, such as shown at 24 in Figure 8, the shaft of which is connected by the worm gearing 25 with a disk 26 which engages a wheel 27 on the end of the rod 9' which carries the pin 7, the disk 26 having a recess 28 therein 100 for receiving the wheel 27 so that the parts can drop the same as they would when the foot pedal has been released.

105 The filling means are constructed as follows:

A tube 29 is threaded in the bottom of the tank 4 and has inlet ports 30 in its upper end

through which the contents of the tank can pass into the tube. A vent pipe 31 passes through the tube and has an extension 31' at its upper end which extends above the tank. 5 A large headed screw 32 holds a gasket 33 against the bottom of the tube 29, with its threaded shank 34 threaded in the bottom of the vent pipe 31. Thus the vent pipe and tube are held in spaced relation with their lower 10 ends closed. A packing member 35 is placed between the lower ends of the tube and pipe, and this member is so shaped that it leaves the liquid discharge port 36 of the pipe 29 free, while preventing liquid from reaching 15 the vent port 37 in said pipe 29. This member 35 has a port 38 therein for connecting the port 37 with a port 39 in the lower end of the vent pipe 31. By this means, fluid from the tank can pass down the space between the 20 tube 29 and pipe 31 and discharge through the port 36 into the bottle A, while the air in the bottle can escape through the ports 37, 38 and 39 into the vent pipe 31. A valve sleeve 40 surrounds the lower part of the tube 25 29 and a spring 41, placed on the tube and sleeve, tends to hold the lower end of the sleeve against the head 32 of the screw, thus closing the ports 36 and 37. The lower end of the sleeve 40 also carries a ring-shaped member 30 42, preferably of resilient material, which acts as a seal for the bottle mouth when the bottle is being filled, and this member also acts as means for causing the bottle to move the valve sleeve upwardly to open the ports 35 when the bottle is in filling position.

From the foregoing, it will be seen that as the bottle supporting means are raised, one of the bottles will engage the member 42 with its mouth, thus lifting the valve sleeve 40 so 40 that some of the liquid from the tank 4 can flow into the bottle from the discharge port 36 while the air is venting from the bottle through the ports 37, 38 and 39 into the vent pipe 31. Then as the bottle supporting means 45 are lowered, the spring 41 will return the valve sleeve to lowered position and thus close the ports 36 and 37.

As the bottle supporting means move downwardly, they will be given a quarter turn as 50 above described, so that the bottle just filled will be moved from under the filling means and a new bottle will be brought under the filling means so that as the supporting means are raised again, the new bottle will operate 55 the filling means.

It is thought from the foregoing descrip-

tion that the advantages and novel features of my invention will be readily apparent.

I desire it to be understood that I may make changes in the construction and in the combination and arrangement of the several parts, provided that such changes fall within the scope of the appended claims.

What I claim is:—

1. A device of the class described comprising 65 a supporting frame, a tank carried thereby, a discharge pipe connected with the tank, an air vent pipe in communication with the tank above the liquid level and passing through the first pipe, a closure member detachably connected with the lower end of the vent pipe and closing the lower end of the first pipe, said member being of greater diameter than the first pipe, said pipes having ports therein adjacent their lower ends, one port in the first 70 pipe registering with a port in the vent pipe, a plug in the lower end of the space between the two pipes, said plug having a beveled upper part with its low side arranged adjacent a port in the first pipe so that this port is in 75 communication with the space between the two pipes and the high part of the plug having a port therein for placing the registering ports in communication with each other and a spring pressed valve for normally holding 80 the ports in the first pipe closed, but being moved to open position when a bottle is 85 pressed against the discharge end of the device.

2. A bottle filling machine comprising a 90 tank, a liquid discharge pipe connected with the tank and depending therefrom, a vent pipe passing through the liquid pipe and spaced therefrom, a closure member detachably connected with the bottom of the vent 95 pipe and closing the lower end of the space between the two pipes, said pipes having ports therein adjacent their lower ends, a port in the vent pipe being in alignment with a port in the liquid pipe, a plug in the lower end of the space between the two pipes, said plug leaving a port of the liquid pipe free and having a port therein which registers with the ports which are in alignment with each other, a spring pressed member slidably arranged on the liquid pipe for closing the ports therein and a valve carried by the member and adapted to engage the mouth of a bottle when a bottle is pressed against the device.

In testimony whereof I affix my signature.

EDGAR S. ENGLE.
